UNITED STATES PATENT OFFICE.

HENRY BUSCH, OF LINNTON, OREGON.

TRANSMISSION.

1,405,272.

Specification of Letters Patent. Patented Jan. 31, 1922.

Application filed June 27, 1921. Serial No. 480,595.

To all whom it may concern:

Be it known that I, HENRY BUSCH, a citizen of the United States, and resident of Linnton, county of Multnomah, and State 5 of Oregon, have invented a new and useful Improvement in Transmissions, of which the following is a specification.

The present invention relates to improvements in transmissions and its particular 10 object is to provide a gear mechanism adapted to receive driving power from two different sources, to combine the two powers into one and then transmit it as a single power to the machinery which it is desired 15 to drive. While the general idea involved in my invention may be applied in many ways, I have perfected the same with particular reference to a wave motor, and in the following description I shall illustrate 20 my invention in connection with a wave motor designed by me, without, however, wishing to limit myself thereby in the application of my gear mechanism.

The latter involves a general principle 25 which may be reduced to practice in several different ways. I prefer to use the form illustrated in the accompanying drawings, in which Figure 1 is a cross-section through my gear mechanism, Figure 2 a plan view of 30 a wave motor designed to be used with my gear mechanism, Figure 3 an elevation of a pawl and ratchet mechanism used in my gearing, Figure 4 a cross-section through the gear mechanism shown in Figure 1 35 along line 4—4 of said figure, and Figure 5 a side elevation of the wave motor shown in plan view in Figure 2.

Referring to the drawings in detail, it will 40 be seen that my wave motor is actuated by a float (2) resting on the surface of a liquid in motion, as the water of the sea, and raised and lowered as the waves pass under the same. It is moored to a definite place on the water by any means desired, preferably by 45 the cables (3) secured to the same as shown at 4 and fastened to some stationary support not shown in the drawing. Rotary motion is transmitted from this float to two drums (6) and (7) rotatably mounted on a shaft 50 (8) which latter may be supported in any manner desired, as for instance in the two stationary bearing members (9) and (11). The manner of transmitting the motion is shown somewhat diagrammatically in Figure 55 and comprises two central hooks se-

cured to the float, one (12) at the bottom and the other (14) at the top, which two hooks are connected by two cables (16) and (17). The former leads from the hook (12) over a pulley (18) supported below the float as 60 on the block (19) resting on the bottom of the water, a second pulley (21) adapted to keep the cable clear of the float, to the drum (7), is wound around the same two or more times, and secured to the hook (14). The 65 cable (17) is connected between the two hooks similarly, but is wound on the drum (7) and its winding has the opposite direction of the winding on the drum (6).

It will be readily understood from this 70 arrangement that when the float rises both drums rotate in opposite directions, and when the float falls, both drums turn and again rotate in opposite directions, the result being an oscillating motion of both 75 drums in opposite directions. The latter are provided at either end with circular recesses (22) adapted to receive the ratchet wheels (23), (24), (26) and (27), which are loosely supported on the shaft (8). The teeth of 80 the ratchet (23) run in opposite direction to those of the ratchet (24) and each ratchet wheel is adapted to be driven by a plurality of pawls (25) secured in the flanges (28) forming the recesses, so that the drum (6), 85 viewed from the left, on a clockwise rotation actuates the ratchet wheel (24) and on a counter-clockwise rotation actuates the ratchet wheel (23). The pawls and ratchets for the drum (7) are arranged symmetrically so that, viewed from the left hand side, 90 a clockwise rotation of the drum (7) actuates the ratchet wheel (26), while a counter-clockwise rotation actuates the ratchet (27). Since the drums always oscillate in 95 opposite direction, it will be seen that on one vertical motion of the float the ratchets (23) and (26) are actuated simultaneously and in opposite direction, while on the reversed vertical motion of the float the ratchets (24) and (27) are actuated in opposite directions. 100 Springs (29) hold the pawls in engagement with the ratchets.

In further describing the action of my 105 gear, I shall confine myself to the ratchet wheels (23) and (26) and we will assume that they are actuated by the rising of the float. The machinery to be driven is connected by a belt or other means to the large pulley (31), which rotates on a sleeve (32), 110

the latter being rotatably supported on the shaft (8).

The ratchet wheel (23) transmits through the pinions (30) engaging the internal gear (33) of the stationary bearing member (9) and the gear wheel (34), rotary motion to the shaft (8), which rotates in the same direction as the ratchet wheel, but at an increased speed. The central gear wheel (36), 10 being rigidly secured to the shaft (8), rotates with the same.

The ratchet wheel (26) is rigidly secured to the sleeve (32), which is provided with a flange (37) supporting, near its outer circumference, a plurality of co-axial pins (38) 15 which carry the pinions (39) meshing with the internal gear (41) in the pulley (31) and the gear wheel (36). Remembering that the ratchets (26) and (23) rotate in opposite direction, it will be seen that the gear wheel (36) and the pinion carrying flange (37) 20 rotate in opposite direction. We then have the different motions indicated by the arrows in Figure 4. The gear wheel (36) rotates clockwise, the pinion carrying flange (37) rotates counter-clockwise, as a resultant of which motions the pulley (31) turns counter-clockwise with increased speed.

The following considerations will explain 30 the action of the different gear wheels more clearly. Assuming the flange (37) to be stationary, a clockwise rotation of the gear wheel (36) causes the pinions (39) on the flange to rotate counter-clockwise and the latter rotate the pulley (31) in the same direction. Assuming the gear wheel (36) to be stationary, a counter-clockwise rotation of the flange (37) causes the pulley (31) to rotate counter-clockwise. Now if both the 35 gear (36) and the flange (37) are rotated in opposite direction it will be easily understood that their forces combine in rotating the pulley (31) and that therefore they will rotate the same at an increased velocity.

40 If a rising of the float actuated the ratchet wheels (23) and (26) to combine their strength in operating the pulley (31), a falling of the float will cause the ratchet wheels (24) and (27) to operate the pulley (31) in the same direction, 24 doing the work of 26, and 27 that of 23, so that a continuous rotary 45 motion of the pulley (31) in the same direction is the resultant of all the forces employed.

55 I claim:

1. In means for joining two forces in driving one pulley, a shaft adapted to be driven by one of said forces having a gear wheel thereon, an internal gear in said pulley, a 60 plurality of pinions interposed between the internal gear and the gear wheel in operative relation, and means actuated by the second force for rotating the pinions around the axis of the gear wheel in a direction opposed to 65 the rotary direction of the gear wheel.

2. In means for joining the forces of two co-axial drums rotating in opposite directions in driving one pulley, a gear wheel operatively connected with one of said drums, an internal gear in the pulley, a plurality of 70 pinions interposed between the internal gear and the gear wheel in operative relation and means actuated by the second drum for rotating the pinions around the axis of the gear wheel in a direction opposed to the rotary direction of the gear wheel. 75

3. In means for joining the forces of two co-axial drums oscillating in opposite directions in driving one pulley, two shafts adapted to collect the equi-directional oscillations 80 whereby the shafts are rotated in opposite directions, a gear wheel on one of the shafts, an internal gear in the pulley, a plurality of pinions interposed between the internal gear and the gear wheel in operative relation, and means actuated by the second shaft for rotating the pinions around the axis of the gear wheel in a direction opposed to the rotary direction of the gear wheel. 85

4. In means for joining the forces of two co-axial drums oscillating in different directions in driving one pulley, two ratchet wheels of opposed tooth direction in operative relation to each drum, a plurality of 90 pawls for each drum adapted to transmit equi-directional oscillations of the drum to the ratchet wheels whereby the latter are rotated in opposite directions, a gear wheel operatively connected with two equi-directional ratchet wheels, an internal gear in the pulley, a plurality of pinions interposed between the internal gear and the gear wheel in operative relation, and means actuated by the two ratchet wheels rotating in the opposite direction for rotating the pinions 95 around the axis of the gear wheel in a direction opposed to the rotary direction of the gear wheel. 100

5. In means for utilizing waves in liquids for driving a pulley, or the like, a float on 110 the surface of the liquid secured against lateral motion, two drums in operative proximity to the float, means for operatively connecting the float to the drums whereby oscillating motion is imparted to the drums in 115 opposite directions, two shafts adapted to collect the equi-directional oscillations whereby the shafts are rotated in opposite directions, a gear wheel on one of the shafts, an internal gear in the pulley, a plurality of 120 pinions interposed between the internal gear and the gear wheel in operative relation, and means actuated by the second shaft for rotating the pinions around the axis of the gear wheel in a direction opposed to the 125 rotary direction of the gear wheel. 125

6. In means for utilizing waves in liquids for driving a pulley or the like, a float on the surface of the liquid secured against lateral motion, two drums in operative prox- 130

imity to the float, means for operatively connecting the float to the drums whereby oscillating motion is imparted to the drums in opposite directions, two ratchet wheels of 5 opposed tooth direction in operative relation to each drum, a plurality of pawls for each drum adapted to transmit equi-directional oscillations of the drum to the ratchet wheels whereby the latter are rotated in opposite 10 directions, a gear wheel operatively con-

nected with two equi-directional ratchet wheels, an internal gear in the pulley, a plurality of pinions interposed between the internal gear and the gear wheel in operative relation, and means actuated by the two 15 ratchet wheels rotating in the opposite direction for rotating the pinions around the axis of the gear wheel in a direction opposed to the rotary direction of the gear wheel.

HENRY BUSCH.
